2 Claims. (Cl. 179—171)

1

The present invention relates to an electric pulse repeating circuit containing a pulse transformer and concerns particularly an arrangement for applying magnetic bias to the transformer in order to increase the amplitude of the pulses obtainable therefrom.

It is well known that the magnetic saturation of the core of a transformer practically limits the amplitude of the output pulses. If the core is initially unbiased, the maximum possible amplitude of the output pulse is substantially determined by the saturation value of the flux of the core. When the pulses are unidirectional, the core may be biased practically to saturation in the negative direction and then if the input pulse be applied so as to change the flux in the positive direction, the total flux change available for the production of the output pulse will now be twice the saturation flux.

The present invention comprises a thermionic valve amplifier for pulses including a transformer from which the output pulses are obtained, and in which the transformer is magnetically biased by a current derived from an electrode of one of the amplifying valves, so that a biasing flux is produced in opposition to the flux produced by the pulses.

The invention will be described with reference to the accompanying drawing in which:

Fig. 1 shows a schematic circuit diagram of an embodiment; and

Fig. 2 shows a hysteresis curve used to explain the operation of the circuit of Fig. 1.

Referring to Fig. 1, there is shown a pulse amplifier comprising two valves V1 and V2 shown for example as triodes, though any suitable valves having additional electrodes may also be used. Unidirectional pulses are applied to the valve V1 at the terminals IN through a blocking condenser C1 with such polarity as to drive the control grid negative. The anode of V1 is coupled to the control grid of V2 through a blocking condenser C2 and resistance R1 and the output pulses are obtained from a transformer T with a core of iron or other magnetic material having its primary winding 1, 2 connected in series with the cathode of V2, and its output secondary winding 3, 4 connected to a load represented by the resistance R2. G1 and G2 are grid leak resistances for the valves V1, and V2 respectively, and A1 and A2 are appropriate anode series resistances. Cathode bias for the valve V1 is provided by the resistance R3 shunted by the condenser C3 and for the valve V2 by the resistance R4 shunted by the condenser C4.

2

A bias winding 5, 6 of the transformer T is connected in series with R3 so that it will be traversed by the steady cathode current of the valve V1. The terminals of the transformer windings are numbered in such a manner that the flux produced by a current which flows from an odd numbered terminal to an even numbered terminal is in the same direction for all the windings.

10 The action of the transformer will be explained with reference to Fig. 2 which shows a typical hysteresis curve for a transformer core. Assuming that no pulses are applied to the valve V1, and that the winding 5, 6 is first disconnected, then the cathode current of valve V2 flowing through the winding 1, 2 will be supposed to produce a small magnetic field in the core given by the length OS. The winding 5, 6 being now re-connected, a superposed magnetic field in the opposite direction is produced by the cathode current of V1. This opposing magnetic field is much larger and is represented by SN. The core is thus brought to the condition represented by the point P, the corresponding flux 25 being represented by PN.

Now assume that a pulse is applied to the control grid of V1 in the negative direction, and of sufficient amplitude to reduce the cathode current to zero. At the same time a positive pulse is obtained at the anode of V1 and this will be applied to the control grid of V2, increasing the cathode current which flows through the winding 1, 2 of the transformer. The magnetic field due to the cathode current of V1 is substantially unaltered because of the large by-pass condenser C3 through which the pulse passes, but the field due to the cathode current of V2 alone increases from OS to OL. The point L is beyond the saturation point of the core, but the presence of the biasing field SN effectively shifts the point 30 L to M. The actual field change is such as to shift the point N over to M, and the operating point travels along the branch PTQ of the curve, the flux changing from PN to QM. A positive pulse will thus be obtained in the load R2 whose amplitude is proportional to 2 PN, if ON=OM. When the pulse disappears, the operating point 35 returns to P over the branch QUP.

The positions of the points S and M can be 40 selected by suitably choosing the number of turns of the winding 1, 2 and the bias of the valve V2. Then the desired opposing field SN can be obtained by suitably choosing the number of turns of the winding 5, 6.

55 The transformer may be connected in various

other ways besides that shown. For example, the bias current may be obtained from the anode circuit of valve V1 and/or the winding 1, 2 may be connected in the anode circuit of V2; or the bias winding could be energised for some other stage (not shown) of the amplifier, or by a screen grid current, for example.

Whatever arrangement is used for biasing the transformer, the bias flux produced by the current in the bias winding should be in the opposite direction to the change in flux produced by the leading edges of the pulses in the primary winding.

Referring again to Fig. 2, the points S, M and N can generally be placed anywhere along the magnetic field axis. This permits a wide choice of the operating curve of the core, and the curve can, for example, be selected so as to obtain the largest possible winding inductance. Alternatively, it can be arranged, if desired, substantially to saturate the core by the bias current, so that an output pulse of maximum amplitude is obtained.

The valve V1 should preferably have a cathode current which is large compared with the cathode current of V2. This permits the winding 5, 6 to have a comparatively small number of turns, so that the loading of the transformer will be only slightly increased by the connection to the cathode circuit of V1. Thus in a particular case of Fig. 1, the cathode currents of the valves V1 and V2 were 100 milliamperes and 6 milliamperes, respectively, and the turns ratio of the windings 1, 2 and 5, 6 was 10:1.

The chief advantage of the arrangement of the invention is that the magnetic bias is obtained without any extra components and without any additional power supplies.

What is claimed is:

1. An amplifier for electric pulses comprising

two thermionic valves, an output transformer having primary, secondary and biasing windings on a core of magnetic material, means to connect the primary winding to the output of one of the said valves, and means to supply current to an electrode of the other valve through the said biasing winding in such a manner as to generate in the said core a flux in opposition to the flux produced therein by pulses transmitted through the said transformer.

2. An amplifier for electric pulses comprising input and output thermionic valves connected in tandem, an output transformer having primary, secondary, and biasing windings on a core of magnetic material, means to apply pulses to the control grid of the input valve, means to connect the said primary winding in series with the cathode of the output valve in such manner as to permit amplified pulses to be derived from the said secondary winding, and means to pass the steady cathode current of the input valve through the said biasing winding in such a manner that the flux produced in the said core produced by pulses transmitted through the transformer is in opposition to the flux produced by the said steady cathode current.
